UNITED STATES PATENT OFFICE.

JOHN CHARLES HENDERSON, OF SAN FRANCISCO, CALIFORNIA.

PISTON-RING.

1,214,303.

Specification of Letters Patent. Patented Jan. 30, 1917.

Application filed October 17, 1914. Serial No. 867,109.

To all whom it may concern:

Be it known that I, JOHN C. HENDERSON, a citizen of the United States, residing at the city and county of San Francisco and State of California, have invented new and useful Improvements in Piston-Rings, of which the following is a specification.

This invention relates to that class of piston rings which is known as leak-proof or jointless.

It is one of the objects of the present invention to provide a simple, durable, cheaply manufactured piston ring of the character described which is not only without a transverse opening extending entirely through the ring and expansible circumferentially, but which is also expansible in the direction of the longitudinal axis of the piston, thus maintaining a tight joint in the piston groove which eliminates knocking of the ring in the piston groove and also prevents leakage around the edges of the ring through the groove.

Further objects will hereinafter appear. The invention consists of the parts and the construction and combination of parts as hereinafter more fully described and claimed, having reference to the accompanying drawings, in which—

Fig. 1 is a perspective view of the ring. Fig. 2 is a perspective view of the outer ring section. Fig. 3 is a perspective view of the inner ring section. Fig. 4 is a section of a piston showing the application of the rings.

More particularly described, the piston ring comprises a pair of telescoping rings 2 and 3, both split throughout their depth, as indicated respectively at 4 and 5. The inner or major ring 2 embraces the piston, and the inside wall of said ring is straight, as indicated at 6, while the outer wall is tapered cone-like, as at 7, and terminates in an annular base flange 8 which forms a seat for the outer or minor ring 3. The exterior wall of this ring is straight, as at 9, to fit the inner wall of the cylinder, while the inner surface is tapered, as at 10, to fit the tapered exterior surface 7 of ring 2.

When the rings are assembled the splits will stand diametrically opposite to each other, as shown in Fig. 1. Ring 3 will thus overlap split 4 in ring 2 while flange 8 will close split 5 in ring 3. The transverse opening which would otherwise be formed through each ring is thus closed, it being

clear that without this overlapping construction a transversely extending opening in the ring would be formed between the ends of the ring which, when the ring is in use, would result in leakage. Thus it will be seen that with the construction set forth the joints at the respective ends of the sections or component parts of the ring will be tightly closed precluding the possibility of leakage through the ring when in use.

The tapering, cone-like inner and outer surfaces of the respective rings tend to crowd the rings away from each other against the upper and lower walls 12 and 13 of the piston groove. This crowding action of one ring with relation to the other automatically takes up all wear at these points and not only eliminates knock or play of the rings within the grooves but always insures a tight joint which will positively eliminate any leakage around the rings.

The ring sections are formed of spring metal, such as cast iron or the like, so as to permit of the same being expanded in order to slide the rings over the piston head into engagement with the annular grooves usually provided in the piston head for the reception of the rings. After being arranged in position in the grooves, the resiliency of the sections serves to press the latter outwardly into engagement with the walls of the cylinder in order to establish a tight joint as is readily understood by those skilled in the art.

The sections fit one within the other, as shown, and the contact of the outer ring with the piston wall prevents same from turning with relation to the piston. Flange 8 of the inner ring similarly contacts with the cylinder wall and the cone-like outer face of the ring will at the same time engage with the inner tapered face of the outer ring. The rings are thus frictionally locked together and prevented from turning with relation to each other and no interlocking pin will be needed, as the area of the contacting surfaces of the rings just described, together with that presented against the piston wall, is much greater than the area presented by the edge of each ring against the upper and lower walls of the piston grooves.

The materials and finish of the several parts of the piston ring are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

10. 1. A piston ring comprising inner and outer split spring rings having a tendency to expand outwardly, a flange on one edge of said inner ring forming an abutment for the outer ring, an exterior cone-like surface on said inner ring extending from the flange to the opposite edge of the ring, and an interior cone-like surface on the outer ring extending the entire width thereof and contacting with the corresponding cone-like surface on the inner ring, and adapted to slide laterally thereon.
15. 2. A piston ring comprising inner and outer split rings having a spring-like tendency to expand outwardly, a flange on said inner ring forming an abutment for the outer ring, an exterior cone-like surface on the inner ring, and an interior cone-like surface on the outer ring, said outer ring being of less width than the inner ring and terminating even with one edge thereof, the construction being such that said cone-like surfaces constitute the entire bearing surface between said rings so that the outer ring is free to slide laterally on the inner ring, and the area of said outer ring contacting with the cylinder wall being less than the area of the conical bearing surfaces.
20. 3. A piston ring comprising inner and outer split spring rings having a tendency to expand outwardly, a flange on one edge of one ring forming an abutment for the other ring, a cone-like surface on the flanged ring extending from said flange to the opposite edge of said ring, and a cone-like surface on the other ring extending the entire width thereof and contacting with the corresponding cone-like surface on the flanged ring, and adapted to slide laterally thereon.
25. 4. A split ring comprising inner and outer split spring rings having a tendency to expand outwardly, a flange on one edge of one ring forming an abutment for the other ring, a cone-like surface on the flanged ring extending from said flange to the opposite edge of said ring, and a cone-like surface on the other ring extending the entire width thereof and contacting with the corresponding cone-like surface on the flanged ring, and adapted to slide laterally thereon.

In testimony whereof I have hereunto set my hand in the presence of two subscribing witnesses.

JOHN CHARLES HENDERSON.
